QUICK ACTION PRESSER FOOT

Harold J. Le Vesconte, Western Springs, Ill., assignor to Union Special Machine Company, Chicago, Ill., a corporation of Illinois

Application July 21, 1939, Serial No. 285,696

7 Claims. (Cl. 112—235)

This invention relates to sewing machines, and is especially concerned with means for holding and feeding the work, such as the device commonly known as a "presser foot."

In sewing machines operating at high speeds (such as 4000 to 7000 or more stitches per minute), difficulty is often experienced in feeding the fabric properly and without injury. The higher the speed of the sewing, the greater the pressure that is required at the presser foot to make the machine feed properly: with lower pressures at the presser foot, the machine may even fail to feed the fabric at all at high speeds. Light weight fabrics are often marked or stretched by the pressure and friction of the presser foot; while for heavy fabrics, the pressure has to be so great that the expenditure of power to operate the machine becomes excessive, the wear on the presser foot and the associated mechanism is very severe, and other drawbacks are encountered. These difficulties, I have found, are due to inability of the usual springs to return the presser foot and the associated parts as rapidly as the feed dog descends, so that it loses effective feeding engagement with the work. Upward momentum of the presser bar and foot at the top of the feed dog rise may also tend to reduce the feeding pressure between the dog and the work objectionably.

Efforts have been made to obviate difficulties in feeding work at high sewing speeds by modifying the usual presser bar arrangement so that while the presser bar weight rests on the presser foot, the effective spring pressure on the presser foot is exerted independently of the presser bar. Such arrangements have not, however, proved practically successful at high speeds.

I have devised a simple and effective presser foot mechanism which overcomes these drawbacks, and in which the presser foot is carried by supporting means which may conveniently be constructed and arranged very much like the usual presser bar, but which does not normally move up and down with the presser foot in sewing, like the ordinary presser bar, but rather remains stationary. The presser foot is held against the work by resilient means acting through a leverage interposed between the foot and said means. Even with a light spring for this purpose, the action of the presser foot is very rapid, and the machine feeds the work properly and without damage at very high speeds.

Various features and advantages of the invention will appear from the following description of species or forms of embodiment, and from

the drawings. All the features and combinations shown or described are, indeed, of my invention, so far as novel over the prior art.

In the drawings,

Fig. I is an end view of a (lockstitch) sewing machine embodying the invention, from in front of the line of stitch formation and work travel.

Figs. II and III are fragmentary views of the presser foot and associated parts from the right and left of Fig. I, the needle and needle bar being broken away.

Fig. IV shows a section taken as indicated by the line and arrows IV—IV in Fig. I.

Fig. V is a fragmentary plan view of parts of the presser foot mechanism, the presser foot itself being omitted.

Fig. VI is a view similar to Fig. I illustrating a modification of the presser foot mechanism shown in Fig. I; and

Figs. VII, VIII, and IX are fragmentary views similar to Figs. II, III, and V.

Fig. I is a view of a sewing machine from in front of the line of stitch formation and work travel, the work support 20 and the stitch plate 21 appearing edgewise. The horizontal arm of the machine frame 22 is concealed by the sewing head 23, which is shown with its cover plate removed to reveal the parts within. The upright needle bar 24, with its needle 25, is mounted for up and down movement in suitable bearings in the head 23, and may be actuated by any suitable means, which need not be described. Beneath the stitch plate 21 is shown a feed dog or member 26 which may be given up and down movements and to and fro movements by any suitable means, not shown, such as a four-motion feed mechanism. Adjacent the needle bar 24 is shown an upright supporting rod or bar 29 equipped with a presser foot 30, with which the feed member 26 coacts through the stitch plate 21. As here shown, the bar 29 is urged downward and held down, during sewing, by a helical compression spring 31 acting between a part 32 suitably secured to the bar (as by a set screw) and a bearing and abutment sleeve 33 screw-threaded through the top of the sewing head 23, and adjustable up and down therein to control and vary the initial tension of the spring 31. On occasion, the bar 29 may be raised for insertion or removal of the work (before or after the sewing of a seam) by any suitable means—as by a foot-treadle-operated lever 34 fulcrumed on the horizontal machine frame arm at 35 and connected by a link 36 to a part 32 suitably secured to the bar, as by a set-screw, or by a hand

lever and cam device 37 fulcrumed on the head 23 at 38, and engaging a part 39 suitably secured to the bar 29. Fig. I also shows thread guides 41, 42, 43, a frictional thread tension device 44, and a suitably actuated take-up lever 45.

The parts thus far mentioned may be of any usual or suitable type and construction, and hence need not be further described.

The presser foot 30 is not fixed to the supporting bar 29, but is mounted thereon so as to be movable up and down relative thereto, and is held down on the work, during sewing, by resilient means carried by and reacting against the bar, such as a spring 46. As here shown, the presser foot 30 has vertical rectilinear motion relative to the bar 29. The presser foot shank 48 may be attached by a screw to a guide block 49 that slides up and down on a headed guide pin 50 attached to a transverse bracket 51 which projects (to the left) from the bar 29. A multiplying leverage is interposed between the presser foot 30 and the spring 46, so that the up and down motion or deflection of the spring corresponding to the normal up and down movement of the presser foot in sewing is very slight—in fact, only a minor fraction of that of the presser foot. The spring 46 is here shown as a cantilever leaf spring attached at one end and bearing at its other end on a multiplying lever 52 near its fulcrum pivot 53 in the forked outer end of the bracket 51. The tension of the spring 46 may be adjusted by any suitable means, such as a screw 54 threaded through the bracket 51 and bearing on the spring intermediate its ends. As shown, this screw 54 is equipped with a lock nut. The bracket 51 may be detachably mounted and secured on the reduced lower end of the bar 29 by means of one or more set-screws. The block 49 may be prevented from turning on the guide pin 50 by a lug 56 on the block engaged in a vertical slot in a guide plate 57 screwed fast to the bracket 51, all as illustrated in Fig. VIII—which is further referred to hereinafter. The up-bent right-hand end of the spring 46 is attached or anchored by a screw 58 to the corresponding (right-hand) end of the bracket 51, and its other or free end bears downward on the lever 52 intermediate its fulcrum pivot 53 on the forked outer end of the bracket 51 and the other or free end of the lever, which in turn bears downward on the block 49. Thus the lever 52 operates as a lever of the third class. As shown, the distance from the fulcrum 53 of the lever 52 to the point of engagement of the spring 46 therewith is only about $\frac{1}{4}$ to $\frac{1}{5}$ the length of the lever, so that the deflection of the spring is only a corresponding fraction of the up and down movement of the presser foot 30.

The downward movement of the supporting bar 29 relative to the sewing head 23 may be limited by any suitable stop means, such as a collar 60 adjustably secured to the bar by a set-screw 61 and engaging against the lower wall of the head 23 as indicated at 62. The downward movement of the presser foot relative to the bar 29, when the latter is raised by the lever 34 or 37, may be limited by any suitable means, such as the head of the guide pin 50.

In practice, the springs 31 and 46 are so designed and their tensions are so adjusted (by means of the sleeve 33 and the screw 54) that there is considerable downward pressure on the supporting bar 29 holding its stop collar 60 against the head 23 at 62 when the presser foot 30 engages the stitch plate 21 with the spring 46

only slightly stressed. In general, spring 46 is made considerably lighter or of smaller scale than the spring 31. During sewing, the spring 46 normally yields to permit upward displacement of the presser foot 30, relative to the bar 29, by the coacting feed member 26; but ordinarily there is no movement or upward displacement of the supporting bar 29—since the greatest stress of the spring 46 during the upward movement of the feed dog leaves the force of this spring 46 still too weak to overcome the initial tension of the spring 31 and lift the stop collar 60 of the bar 29 off its coacting stop surface at 62. In other words, the bar 29 is normally held stationary or fixed against movement relative to the work support 20, during sewing—and it might even be fastened in a fixed position, were it not for the desirability of lifting it to lift the presser foot 30 for insertion and removal of work from time to time. Under some circumstances, also, the spring 31 may serve a useful purpose by yielding in case some extraordinary local thickness of the work should require extraordinary upward displacement of the presser foot. When the bar 29 is lifted, the presser foot 30 is also lifted well clear of the work, as a result of the engagement of the head of pin 50 with the guide block 49 soon after the bar 29 begins its upward movement from the position shown in Fig. I.

In reality, then, the part 29 is not a presser bar in the usual meaning of this term, but a means of supporting the movably mounted presser foot 30 and the associated parts, and of guiding and confining the foot to a fixed path of movement, and is also made to serve as a means of lifting the presser foot, when desired, by means of the connection provided by the guide block 49 and the head of the pin 50. The only movable parts are the presser foot 30 with its shank 48 and block 49, and the lever 52, which are in the aggregate quite light, while the deflection of the spring 46 in operation is very slight. Accordingly, this presser foot mechanism is capable of very rapid operation.

The arrangement and construction shown in Figs. VI—IX is in the main similar to that shown in Figs. I—V, but has the bracket 51a, the spring 46, and the lever 52 arranged at right angles to the line of stitching and work feed, and thus extending to the rear in Fig. VI. This allows freer access to the work behind the presser foot 30a. Figs. VI—IX also illustrate minor variations of construction: e. g., the shank 48 is attached to the block 49 by a screw-threaded stud and nut, instead of by a screw as in Figs. I—V. However, the operation of this mechanism is substantially the same as that of the mechanism illustrated in Figs. I—V.

Having thus described my invention, I claim:

1. The combination in a sewing machine having a work support, a presser-foot support normally held against movement from and toward said work support during sewing, and a presser foot slidably guided by said presser-foot support toward and from said work support, during sewing, of spring means carried by said presser-foot support and reacting thereagainst, and a lever of the third class operatively interposed between said spring means and said presser foot and transmitting the pressure of the spring means to the presser-foot to urge the latter toward said work support.
2. The combination in a sewing machine having a work support, a presser-foot support normally held against movement from and toward

said work support, during sewing and carrying presser-foot guide means, and a presser-foot slidably guided by said guide means for movement relative to said presser-foot support toward and from said work support, during sewing, of spring means carried by said presser-foot guide means and reacting thereagainst, and a lever fulcrumed on said presser-foot support operatively interposed between said spring means and said presser-foot, and transmitting the pressure of the spring means to the presser foot to urge the latter toward said work support.

3. The combination in a sewing machine having a work support, a presser-foot support normally held against movement from and toward said work support, during sewing, and provided with rectilinear guide means, and a presser foot mounted on and movable along said guide means, during sewing, toward and from said work support, of a lever fulcrumed on said presser-foot support at one end and acting on said presser foot at its other end, and spring means carried by said presser-foot support acting on said lever between its fulcrumed end and its other end, where it acts on said presser foot, and urging the latter toward said work support.

4. The combination in a sewing machine having a work support, a presser-foot support normally held against movement from and toward said work support, during sewing, and provided with rectilinear guide means, and a presser foot mounted on and movable along said guide means, during sewing, toward and from said work support, of a lever fulcrumed on said presser-foot

5 support at one end and acting on said presser foot at its other end, and a cantilever spring extending lengthwise of the lever and transversely of said guide means attached to said presser-foot support at one end and at its other end acting on said lever between its fulcrum and its operative connection to said presser foot, and urging the latter toward said work support.

10 5. The combination as set forth in claim 4 wherein the presser-foot support comprises a bracket transverse to said guide means, and the lever and cantilever spring are mounted on opposite ends of said bracket, respectively.

6. The combination as set forth in claim 4 wherein the presser-foot support comprises a bracket transverse to said guide means, and the lever and cantilever spring are mounted on opposite ends of said bracket, respectively with an adjusting screw threaded in said bracket at an intermediate point in the length of the bracket bearing on said spring at an intermediate point in the length of the spring between its attachment to the bracket and its end bearing on the lever.

20 25 7. The combination as set forth in claim 4 wherein the presser-foot support comprises a supporting rod extending in the general direction of the presser-foot movement toward and from the work support, and a bracket projecting to one side from said rod, and the lever is fulcrumed on the end of the bracket remote from said rod, while the spring is attached to the bracket adjacent said rod.

HAROLD J. LE VESCONTE.
